UNITED STATES PATENT OFFICE.

WILLIAM RUSSELL CUMMINS, OF GLASGOW, SCOTLAND.

INTERNAL-COMBUSTION ENGINE.

1,845,911.

Specification of Letters Patent.

Patented July 6, 1920.

Application filed November 20, 1918. Serial No. 263,299.

To all whom it may concern:

Be it known that I, WILLIAM RUSSELL CUMMINS, a subject of the King of Great Britain and Ireland, and of 1 Grosvenor 5 Terrace, Hillhead, Glasgow, Scotland, have invented new and useful Improvements in Internal-Combustion Engines, of which the following is a specification.

This invention refers to two stroke cycle

- 10 internal combustion engines of the type comprising a power cylinder, an auxiliary cylinder extending outwardly from, of greater diameter than and co-axial with the power cylinder, a cylindrical guide within 15 the auxiliary cylinder co-axial therewith, a connecting rod crosshead fitting within and adapted to reciprocate in the guide, a piston for the power cylinder connected to the crosshead, and an annular piston for the 20 auxiliary cylinder connected to the power piston by a tubular sleeve, so arranged that as the power piston reciprocates, the outward movement of the auxiliary piston produces a suction stroke in the annular space 25 contained between the walls of the auxiliary cylinder and the tubular sleeve due to the piston moving away from the inner end of the auxiliary cylinder, and the inward movement produces a compression stroke, the effects of which are used for scavenging or 30 delivering supplies of combustible mixture to the power cylinder.

The object of this invention is to make provision in engines of this type for causing 35 a substantial quantity of air to be circulated in the region about the outer face of the power piston for cooling purposes, and in some cases also to obtain cushioning effects.

In constructing a two stroke cycle internal combustion engine according to this invention, the outer end of the annular space, contained between the walls of the auxiliary cylinder and the cylindrical guide for the crosshead, is closed to form a circulation 40 chamber, a hollow trunk is provided to connect the crosshead with the power piston, ports are formed extending through the walls of the trunk in the region about the outer face of the power piston and a passage 45 is formed extending between the walls of the tubular sleeve (which connects the power piston with the auxiliary piston) and the trunk, so that as the power piston reciprocates, the outward movement of the auxiliary piston produces a compression stroke 50 in the circulation chamber due to its mov-

ing toward the outer end of the chamber, and the inward movement a suction stroke, whereby air is caused to be circulated in the region about the outer face of the power 60 piston.

Some examples of construction according to this invention will now be described with reference to the accompanying drawings, in which:—

Figures 1, 2 and 3 are longitudinal sections illustrating constructions embodying various modifications. Fig. 4 is a longitudinal section showing a portion of a power piston with associated parts.

In the drawings, A designates the power cylinder of the engine, B the auxiliary cylinder of greater diameter which extends outwardly from the power cylinder, C the cylindrical guide within the auxiliary cylinder, 75 D the connecting rod crosshead fitting within and adapted to reciprocate in the guide, E the piston of the power cylinder, and F the annular piston of the auxiliary cylinder which is connected to the power piston 80 by a tubular sleeve G. In the operation of engines of the type defined, the outward movement of the auxiliary piston F produces a suction stroke in the annular space contained between the walls of the auxiliary 85 cylinder B and the tubular sleeve G due to its moving away from the inner end of the cylinder B, and the inward movement produces a compression stroke for the purpose of scavenging or delivering supplies 90 of combustible mixture to the power cylinder A, as is well understood.

The improvements according to this invention consist as exemplified in the constructions illustrated in providing means, 95 such as the cover H, for closing the outer end of the annular space contained between the walls of the auxiliary cylinder B and the cylindrical guide C in order to form a circulation chamber, the provision of a hollow 100 trunk, such as J, connecting the crosshead D with the power piston E, ports, such as K, extending through the walls of the trunk J in the region about the outer face of the power piston E, and a passage, such as L, 105 extending between the walls of the tubular sleeve G and the trunk J, whereby as the engine operates the outward movement of the auxiliary piston F produces a compression stroke in the circulation chamber due 110 to its moving toward the outer end of the chamber causing air to be expelled there-

2
from and to pass through the passage L to the ports K into the hollow interior of the trunk J, and in so doing circulate in the region about the outer face of the power 5 piston E and the inward movement of the auxiliary piston F produces circulation of air in the reverse direction.

As shown at Figs. 1 and 2, deflectors such as M may be provided for directing the air 10 against the outer face of the power piston, and in order to increase the cooling surface, parts projecting from the outer face of the power piston, such as ribs N, see Fig. 1, or 15 heat conductors N¹, see Fig. 3, may be provided. These conductors N¹, as shown at Fig. 4, may consist of open ended tubes projecting from the outer face of the piston E.

In the construction shown at Fig. 1, the outer end of the trunk J is open, in which 20 case air may circulate freely into and out of the trunk so that the air used is constantly changing. With this arrangement no appreciable cushioning effect would be obtained.

25 In the constructions shown at Figs. 2 and 3, the outer end of the trunk is closed by a partition J¹, in which case the circulation produced is of the air inclosed within the circulation chamber, the passage L, and the 30 interior of the trunk J. With this arrangement a cushioning effect is produced by the air compressed in the circulation chamber as the piston F completes its outward stroke. As the extent to which the inclosed air is 35 circulated depends partly upon the clearance in the circulation chamber and the area of the passage L, these may be reduced as far as practicable. The air used under these conditions, and, if desired, in constructions 40 such as illustrated at Fig. 1, may be cooled within the circulation chamber by providing means through which a cooling medium is adapted to be circulated. For instance, the cylindrical guide C may be surrounded 45 by a coil P, see Fig. 2, or by a jacket P¹, see Fig. 3. Further, the passage L may be furnished with ribs R, see Fig. 3, extending from the walls of the tubular sleeve G for the transference of heat.

50 I claim:

1. A two stroke cycle internal combustion engine of the type defined, comprising an auxiliary cylinder, a power piston, a cylindrical cross-head guide, an annular piston in 55 said auxiliary cylinder, a tubular sleeve connecting said annular piston and power piston and having in combination a circulation chamber contained between the walls of the auxiliary cylinder and the cylindrical guide 60 for the crosshead closed at its outer end, a hollow trunk connecting the crosshead with the power piston, ports extending through the walls of the trunk in the region about the outer face of the power piston, deflectors 65 within the hollow interior of the trunk, and

a passage extending between the walls of the tubular sleeve and the trunk, for the purposes set forth.

2. A two stroke cycle internal combustion engine of the type defined, comprising an auxiliary cylinder, a power piston, a cylindrical cross-head guide, an annular piston in 70 said auxiliary cylinder, a tubular sleeve connecting said annular piston and power piston and having in combination a circulation chamber contained between the walls of the auxiliary cylinder and the cylindrical guide 75 for the crosshead closed at its outer end, a hollow trunk connecting the crosshead with the power piston, ports extending through the walls of the trunk in the region about the outer face of the power piston, parts 80 projecting from the outer face of the power piston, and a passage extending between the walls of the tubular sleeve and the trunk, for the purposes set forth.

3. A two stroke cycle internal combustion engine of the type defined, comprising an auxiliary cylinder, a power piston, a cylindrical cross-head guide, an annular piston 90 in said auxiliary cylinder, a tubular sleeve connecting said annular piston and power piston and having in combination a circulation chamber contained between the walls of the auxiliary cylinder and the cylindrical 95 guide for the crosshead closed at its outer end, a hollow trunk connecting the crosshead with the power piston, ports extending through the walls of the trunk in the region about the outer face of the power piston, 100 open ended tubes projecting from the outer face of the power piston, and a passage extending between the walls of the tubular sleeve and the trunk, for the purposes set forth.

105 4. A two stroke cycle internal combustion engine of the type defined, comprising an auxiliary cylinder, a power piston, a cylindrical cross-head guide, an annular piston in said auxiliary cylinder, a tubular sleeve 110 connecting said annular piston and power piston and having in combination a circulation chamber contained between the walls of the auxiliary cylinder and the cylindrical guide for the crosshead closed at its outer 115 end, a hollow trunk closed at its outer end connecting the crosshead with the power piston, ports extending through the walls of the trunk in the region about the outer face of the power piston, and a passage extending between the walls of the tubular sleeve 120 and the trunk, for the purposes set forth.

125 5. A two stroke cycle internal combustion engine of the type defined, comprising an auxiliary cylinder, a power piston, a cylindrical cross-head guide, an annular piston in said auxiliary cylinder, a tubular sleeve connecting said annular piston and power piston and having in combination a circulation chamber contained between the walls of 130

- the auxiliary cylinder and the cylindrical guide for the crosshead closed at its outer end, a hollow trunk connecting the crosshead with the power piston, a partition at 5 the outer end of the trunk, ports extending through the walls of the trunk in the region about the outer face of the power piston, deflectors within the hollow interior of the trunk, and a passage extending between the 10 walls of the tubular sleeve and the trunk, for the purposes set forth.
6. A two stroke cycle internal combustion engine of the type defined, comprising an auxiliary cylinder, a power piston, a cylindrical cross-head guide, an annular piston 15 in said auxiliary cylinder, a tubular sleeve connecting said annular piston and power piston and having in combination a circulation chamber contained between the walls of 20 the auxiliary cylinder and the cylindrical guide for the crosshead closed at its outer end, a hollow trunk connecting the crosshead with the power piston, a partition at the outer end of the trunk, ports extending 25 through the walls of the trunk in the region about the outer face of the power piston, parts projecting from the outer face of the power piston, and a passage extending between the walls of the tubular sleeve and 30 the trunk, for the purposes set forth.
7. A two stroke cycle internal combustion engine of the type defined, comprising an auxiliary cylinder, a power piston, a cylindrical cross-head guide, an annular piston 35 in said auxiliary cylinder, a tubular sleeve connecting said annular piston and power piston and having in combination a circulation chamber contained between the walls of the auxiliary cylinder and the cylindrical 40 guide for the crosshead closed at its outer end, a hollow trunk connecting the crosshead with the power piston, a partition at the outer end of the trunk, ports extending through the walls of the trunk in the region 45 about the outer face of the power piston, open ended tubes projecting from the outer face of the power piston, and a passage extending between the walls of the tubular sleeve and the trunk, for the purposes set 50 forth.
8. A two stroke cycle internal combustion engine of the type defined, comprising an auxiliary cylinder, a power piston, a cylindrical cross-head guide, an annular piston 55 in said auxiliary cylinder, a tubular sleeve connecting said annular piston and power piston and having in combination a circulation chamber contained between the walls of the auxiliary cylinder and the cylindrical 60 guide for the crosshead closed at its outer end, means within the circulation chamber through which a cooling medium is adapted to be circulated, a hollow trunk connecting the crosshead with the power piston, ports 65 extending through the walls of the trunk in

the region about the outer face of the power piston, and a passage extending between the walls of the tubular sleeve and the trunk, for the purposes set forth.

9. A two stroke cycle internal combustion 70 engine of the type defined, comprising an auxiliary cylinder, a power piston, a cylindrical cross-head guide, an annular piston in said auxiliary cylinder, a tubular sleeve connecting said annular piston and power 75 piston and having in combination a circulation chamber contained between the walls of the auxiliary cylinder and the cylindrical guide for the crosshead closed at its outer end, means within the circulation chamber 80 through which a cooling medium is adapted to be circulated, a hollow trunk closed at its outer end connecting the crosshead with the power piston, ports extending through the walls of the trunk in the region about the 85 outer face of the power piston, and a passage extending between the walls of the tubular sleeve and the trunk, for the purposes set forth.

10. A two-stroke cycle internal combustion engine, comprising a power cylinder, a power piston movable in said power cylinder, an auxiliary cylinder extending outwardly from said power cylinder, said auxiliary cylinder coaxial with and of greater 90 diameter than said power cylinder, an annular piston movable in said auxiliary cylinder, a tubular sleeve connecting said power piston and said annular piston, a cylindrical guide within said auxiliary cylinder 95 coaxial therewith, said guide spaced radially from said auxiliary cylinder to afford between the walls of said guide and said auxiliary cylinder a circulation chamber closed at its outer end, a cross-head movable 100 in said guide, a hollow trunk connecting said power piston and said cross-head, said trunk spaced radially from said sleeve to afford between the walls of said trunk and said sleeve a passage communicating with 105 said chamber, said trunk formed with through ports in the region about the outer face of said power piston, and deflectors within said trunk.

11. A two-stroke cycle internal combustion engine, comprising a power cylinder, a power piston movable in said power cylinder, an auxiliary cylinder extending outwardly from said power cylinder, said auxiliary cylinder coaxial with and of greater 115 diameter than said power cylinder, an annular piston movable in said auxiliary cylinder, a tubular sleeve connecting said power piston and said annular piston, a cylindrical guide within said auxiliary cylinder coaxial 120 therewith, said guide spaced radially from said auxiliary cylinder to afford between the walls of said guide and said auxiliary cylinder a circulation chamber closed at its outer end, a cross-head movable in said 125

guide, a hollow trunk connecting said power piston and said cross-head, said trunk spaced radially from said sleeve to afford between the walls of said trunk and said 5 sleeve a passage communicating with said chamber, said trunk formed with through ports in the region about the outer face of said power piston, and parts projecting from the outer face of said power piston.

10 12. A two-stroke cycle internal combustion engine, comprising a power cylinder, a power piston movable in said power cylinder, an auxiliary cylinder extending outwardly from said power cylinder, said auxiliary cylinder coaxial with and of greater diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a cross-head movable in said guide, a hollow trunk connecting said power piston and said cross-head, said trunk spaced radially from said sleeve to afford between the walls of said

15 20 25 30 35 trunk and said sleeve a passage communicating with said circulating chamber, said trunk formed with through ports in the region about the outer face of said power piston and tubes projecting from the outer face of said power piston.

13. A two-stroke cycle internal combustion engine, comprising a power cylinder, a power piston movable in said power cylinder, an auxiliary cylinder extending outwardly from said power cylinder, said auxiliary cylinder coaxial with and of greater diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a cross-head movable in said guide, and a hollow trunk closed at its outer end, said trunk connecting said power piston and said cross-head, said trunk spaced radially from said sleeve to afford between the walls of said trunk and said sleeve a passage communicating with said chamber, said trunk formed with through ports in the regions about the outer face of said power piston.

60 14. A two-stroke cycle internal combustion engine, comprising a power cylinder, a power piston movable in said power cylinder, an auxiliary cylinder extending outwardly from said power cylinder, said auxiliary cylinder coaxial with and of greater

diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a cross-head movable in said guide, a hollow trunk connecting said power piston and said cross-head, said trunk spaced radially from said sleeve to afford between the walls of said trunk and said sleeve a passage communicating with said chamber, said trunk formed with through ports in the region about the outer face of said power piston, and a partition at the outer end of said trunk.

15. A two-stroke cycle internal combustion engine, comprising a power cylinder, a power piston movable in said power cylinder, an auxiliary cylinder extending outwardly from said power cylinder, said auxiliary cylinder coaxial with and of greater diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a cross-head movable in said guide, a hollow trunk connecting said power piston and said cross-head, said trunk spaced radially from said sleeve to afford between the walls of said trunk and said sleeve a passage communicating with said chamber, said trunk formed with through ports in the region about the outer face of said power piston, a partition at the outer end of said trunk, and parts projecting from the outer face of said power piston.

16. A two-stroke cycle internal combustion engine, comprising a power cylinder, a power piston movable in said power cylinder, an auxiliary cylinder extending outwardly from said power cylinder, said auxiliary cylinder coaxial with and of greater diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a cross-head movable in said guide, a hollow trunk connecting said power piston and said cross-head, 130

said trunk spaced radially from said sleeve to afford between the walls of said trunk and said sleeve a passage communicating with said chamber said trunk formed with 5 through ports in the region about the outer face of said power piston, a partition at the outer end of said trunk, and tubes projecting from the outer face of said power piston.

17. A two-stroke cycle internal combustion engine, comprising a power cylinder, a power piston movable in said power cylinder, an auxiliary cylinder extending outwardly from said power cylinder, said auxiliary cylinder coaxial with and of greater 10 diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, means within said circulation 15 chamber through which cooling medium may be circulated, a cross-head movable in said guide, and a hollow trunk connecting said power piston and said cross-head, said trunk spaced radially from said sleeve to afford between the walls of said trunk and said sleeve a passage communicating with said chamber, said trunk formed with 20 through ports in the region about the outer face of said power piston.

18. A two-stroke cycle internal combustion engine, comprising a power cylinder, a power piston movable in said power cylinder, an auxiliary cylinder extending outwardly from said power cylinder, said auxiliary cylinder coaxial with and of greater 25 diameter than said power cylinder, an annular piston movable in said auxiliary cylinder, a tubular sleeve connecting said power piston and said annular piston, a cylindrical guide within said auxiliary cylinder coaxial therewith, said guide spaced radially from said auxiliary cylinder to afford between the walls of said guide and said auxiliary cylinder a circulation chamber closed at its outer end, a 30 cross-head movable in said guide, a hollow trunk closed at its outer end, said trunk connecting said power piston and said cross-head, said trunk spaced radially from said sleeve to afford between the walls of said 35 trunk and said sleeve a passage communicating with said chamber, said trunk formed with through ports in the region about the outer face of said power piston, and means in the path of the medium flowing through 40 said chamber and passage for cooling said medium.

19. In a two-stroke cycle internal combustion engine, in combination with a power cylinder, a power piston reciprocable in said cylinder; a scavenging pump cylinder co-

axial with said power cylinder, a cover closing the front end of said pump cylinder, a scavenging piston reciprocable in said pump cylinder, a cross-head, a cylindrical guide for said cross-head, said guide extending 45 from said cover into said pump cylinder and coaxial with said cylinders, and tubular members connecting said power piston with said scavenging piston and said power piston with said cross-head, said tubular members being coaxial with said cylinders and presenting between them an annular passage, the tubular member connecting said power piston with said cross-head being formed with ports located in the region 50 about the outer face of said power piston and affording communication between the interior of said last named tubular member and said passage, whereby on the reciprocation of said scavenging piston air is caused 55 to be circulated in the region about the outer face of said power piston.

20. In a two-stroke cycle internal combustion engine, in combination with a power cylinder, a power piston reciprocable in 60 said cylinder, a scavenging pump cylinder coaxial with said power cylinder, a cover closing the front end of said pump cylinder, a scavenging piston reciprocable in said pump cylinder, a cross-head, a cylindrical 65 guide for said cross-head, said guide extending from said cover into said pump cylinder and coaxial with said cylinders, and tubular members connecting said power piston with said scavenging piston and said power piston with said cross-head, said tubular members being coaxial with said cylinders and presenting between them an annular passage, the tubular member connecting said power piston with said cross-head being 70 closed at its outer end and formed with ports located in the region about the outer face of said power piston and affording communication between the interior of said last named tubular member and said passage, whereby on the reciprocation of said scavenging piston air is caused to be circulated in the region about the outer face of said power piston.

21. A two-stroke cycle internal combustion engine, comprising a power cylinder, a power piston movable in said power cylinder, an auxiliary cylinder extending outwardly from said power cylinder, said auxiliary cylinder coaxial with and of greater 75 diameter than said power cylinder, an annular piston movable in said auxiliary cylinder, a tubular sleeve connecting said power piston and said annular piston, a cylindrical guide within said auxiliary cylinder coaxial therewith, said guide spaced 80 radially from said auxiliary cylinder to afford between the walls of said guide and said auxiliary cylinder a circulation chamber closed at its outer end, a cross-head mov-

6
able in said guide, a hollow trunk connecting said power piston and said cross-head, said trunk spaced radially from said sleeve to afford between the walls of said trunk and 5 said sleeve a passage communicating with said chamber, said trunk formed with through ports in the region about the outer face of said power piston, and means applied to said power piston to increase the 10 heat dissipating surface thereof.

22. A two-stroke cycle internal combustion engine, comprising a power cylinder, a power piston movable in said power cylinder, an auxiliary cylinder extending outwardly from said power cylinder, said auxiliary cylinder coaxial with and of greater diameter than said power cylinder, an annular piston movable in said auxiliary cylinder, a tubular sleeve connecting said power

piston and said annular piston, a cylindrical 20 guide within said auxiliary cylinder coaxial therewith, said guide spaced radially from said auxiliary cylinder to afford between the walls of said guide and said auxiliary cylinder a circulation chamber closed at its 25 outer end, a cross-head movable in said guide, a hollow trunk connecting said power piston and said cross-head, said trunk spaced radially from said sleeve to afford between the walls of said trunk and said 30 sleeve a passage communicating with said chamber, said trunk formed with through ports in the region about the outer face of said power piston, and means to extract heat from the air circulated through said chamber and said passage.

WILLIAM RUSSELL CUMMINS.
